UNITED STATES PATENT OFFICE

2,334,213

MACHINE FOR MAKING CONTAINER PARTS

John H. Murch, East Orange, N. J., assignor to
American Can Company, New York, N. Y., a
corporation of New Jersey

Application July 26, 1941, Serial No. 464,228

10 Claims. (Cl. 93—36)

The present invention relates to a machine for making fibre container parts and has particular reference to forming and assembling such parts to produce a container end closure unit.

In the manufacture of fibre containers of the character disclosed in United States Patent 2,085,979, issued July 6, 1937, to John M. Hothersall, on Container, the top end member of the container is provided with a closure element which preferably is secured in place with a staple so that the closure element may be opened and closed by bending it adjacent the staple in hinge fashion.

The present invention contemplates the forming of a plurality of such closure elements simultaneously from a single web of material, assembling them with preformed container end members moving adjacent the web, and securing them in place with wire staples to produce complete end closure units ready for assembling with containers.

An object therefore of the invention is the provision of a fibre container end closure unit forming and assembling machine wherein a plurality of closure elements are blanked and formed simultaneously from a web of fibre material, assembled in proper position on preformed end members advanced in a plurality of lines adjacent the path of travel of the web, and are secured in place by wire staples to produce complete end closure units ready for subsequent assembly with containers.

Another object is the provision of such a machine wherein the closure element blank is shaped while being attached to the web and is cut free of the web for a drawing operation that completes the closure element so that it may be assembled with and secured in place on the end member.

Another object is the provision of a machine of this character wherein the severing of the shaped closure element from the web and the drawing operation on the element are performed substantially simultaneously at the same station of the machine.

Numerous other objects and advantages of the invention will be apparent as it is better understood from the following description, which, taken in connection with the accompanying drawings, discloses a preferred embodiment thereof.

Referring to the drawings:

Figure 1 is a side elevation of a machine embodying the instant invention, with parts broken back and shown in section;

Fig. 2 is a horizontal section taken substan-

tially along the broken line 2—2 in Fig. 1, with parts broken away;

Fig. 3 is a longitudinal section taken substantially along the line 3—3 in Fig. 2;

Fig. 4 is an end elevation of the machine as viewed along line 4—4 in Fig. 2;

Fig. 5 is an enlarged sectional detail taken substantially along the line 5—5 in Fig. 2, with parts broken away;

Figs. 6 and 7 are transverse sectional views taken substantially along the respective lines 6—6, 7—7 in Fig. 2, with parts broken away;

Fig. 8 is an enlarged sectional detail taken substantially along the line 8—8 in Fig. 2, with parts broken away;

Fig. 9 is an enlarged longitudinal section taken substantially along the line 9—9 in Fig. 2, with parts broken away;

Fig. 10 is a transverse section taken substantially along the line 10—10 in Fig. 9, with parts broken away;

Fig. 11 is a sectional detail taken substantially along the line 11—11 in Fig. 9, with parts broken away;

Figs. 12, 13, 14 are transverse sections taken substantially along the respective lines 12—12, 13—13, 14—14 in Fig. 2;

Fig. 15 is an enlarged plan view of a portion of the machine shown in Fig. 2, with parts shown in a different position;

Fig. 16 is a sectional detail taken substantially along the broken line 16—16 in Fig. 15, with parts broken away;

Fig. 17 is an enlarged view of a portion of a strip of material from which closure elements are produced in the machine, the strip showing the different steps in forming the elements;

Fig. 18 is a perspective view of a closure element as produced in the machine;

Fig. 19 is a perspective view of an end member to be assembled with the closure element to produce an end closure unit;

Figs. 20 and 21 are perspective views of the assembled end closure unit, Fig. 20 showing the unit prior to being stapled and Fig. 21 showing the same unit after stapling;

Fig. 22 is an enlarged longitudinal section taken substantially along the line 22—22 in Fig. 2; and

Fig. 23 is a transverse section taken substantially along the line 23—23 in Fig. 22.

As a preferred embodiment of the instant invention the drawings illustrate a machine in which closure elements A (Fig. 18) having depressed or drawn plug sections B are cut and formed from a web or strip C (Fig. 17) of paper

board or other fibrous material which is fed through the machine in a step-by-step movement. The web preferably is sufficiently wide to cut and form two closure elements simultaneously from the same web, one each in two rows extending longitudinally of the web.

While the closure elements A are being formed, a procession of pre-formed container end members D (Fig. 19) is advanced parallel with and adjacent each outer edge of the moving web so that there is one line of end members on each side of the web. These end members are fed from suitable stacks of such members and each member is formed with a dispensing hole or aperture E adapted to receive the plug section of a closure element A.

At the proper time after a pair of closure elements A have been severed from the web and are fully formed, they are swept side-wise or laterally in opposite directions to bring them into position over the top of a pair of end members in the processions of such members moving with the web. While in this position the closure elements are assembled with the end members by being forced down onto the latter, the plug sections B of the closure elements being pushed into the dispensing openings E of the end members. The closure elements are thus held tightly in position on the end members by frictional engagement.

Immediately following this assembling operation, a wire staple F (Fig. 21) is driven through the assembled parts adjacent a tab G on the closure element and this staple permanently secures the parts together. This completes the assembling operations and the end closure units thus produced are re-stacked ready for use.

In the machine the advancement of the web C of closure element material and the advancement of the preformed end members D, are carried out along straight line paths of travel and a simple, highly efficient and high speed construction thus obtains. The web C is substantially continuous and may be unrolled from a suitable supply roll in any preferred manner.

The web C as it enters the machine is received on and is fed along a table 31 (Figs. 1, 2, 3, 10 and 13) secured to a bracket 32 bolted to a frame bed 33. The frame bed is bolted to legs 34 which are supported on a base 35 and these parts constitute the main frame of the machine. Hold-down bars 36 disposed above the table prevent upward displacement of the web. These hold-down bars are secured to transverse tie bars 37 and a handle 38 bolted to one of these tie bars is provided for removal of the hold-down bars when desired. The two outer hold-down bars also serve as guide rails for maintaining the web in proper position on the table.

The web C is fed along the table 31 in a step-by-step or intermittent manner by a pair of feed rollers 41, 42 (Figs. 2, 3 and 12) which are located adjacent the outer end of the table. Roller 41 is disposed below the web C and is mounted on a shaft 44 carried in bearings 45 in a bracket 46 bolted to the frame bed 33. The roller is periodically rotated by a ratchet wheel 47 (see also Fig. 1) which is keyed to an outer end of the roller shaft 44. The ratchet wheel is actuated by a pawl 48 mounted on a pivot pin 49 carried in an arm extension 52 of a segment gear 53 loosely mounted on the roller shaft 44 between the ratchet 47 and the adjacent bearing 45.

The segment gear 53 is rocked on its shaft 44 by a meshing segment gear 56 which is mounted on one end of a cross-shaft 57 carried in a bear-

ing 58 in the bracket 46 and in a bearing 59 in the frame bed 33. Adjacent the bearing 59, the shaft 57 carries a cam lever 61 having a cam roller 62 which operates in a cam groove 63 of a barrel cam 64 mounted on a continuously rotating cam shaft 65.

The cam shaft 65 extends longitudinally of the machine along one side of the frame bed 33 and is journaled in a plurality of spaced bearings 66 formed in a trough-like extension 67 of the frame bed. The cam shaft is rotated by a bevel gear 71 (Fig. 2) which meshes with a bevel gear 72 mounted on the upper end of a vertical shaft 73 (Fig. 8) journaled in bearings 74 formed in a housing 75 bolted to the machine base 35 and formed as a part of the leg section 34.

The vertical shaft 73 is rotated by a helical gear 76 which is keyed thereto and which meshes with a helical driving gear 77 mounted on a main drive shaft 78 (see also Fig. 6) which extends transversely of the machine near the center thereof. This drive shaft is journaled in bearings 79 in the housing 75 and in a plurality of spaced bearing brackets 81 which are bolted to the machine base 35. The shaft is driven in any suitable manner in time with the other moving parts of the machine.

The feed roller 42 (Figs. 1, 2, 3 and 12) is located above the web C and is mounted on a shaft 85 carried in side arms 86. The arms are mounted on pivot pins 87 carried in lugs 88 formed on the bracket 46. This roller 42 constitutes a pressure roller which presses the web C down tightly against the feed roller 41. The pressure is exerted by compression springs 91 (Fig. 1) which are seated against the top edge of the side arms 86. The springs are held in place by lock-nuts 92 threaded on long studs 93 which extend down through the springs and the arms and are secured in the bracket 46.

The pressure roller 42 rotates in unison with the feed roller 41 for advancing the web C into the machine. For this purpose the pressure roller shaft carries a spur gear 95 (Fig. 12) which meshes with a similar gear 96 mounted on the feed roller shaft 44.

As the web C is advanced in its step-by-step movement along the table 31, it enters a cutting and forming mechanism 101 which produces various stages of completion of the closure elements A in different parts of the web. It is at the cutting step that irregular shaped and staggered areas K (Fig. 17) are cut out from the middle of the strip. This forms part of the boundary of four of the closure elements.

At the same operating stroke of the cutting mechanism and in different positions, two slots L are cut in what will be two of the tabs G. Also two substantially triangular areas M are cut away from opposite edges of the web to shape the fronts of two of the closure elements. The cutting away of the areas K, L and M at each step of cutting removes all waste and shapes blanks N for the closure elements but what will be the individual blanks remain integral with the web until severed at a subsequent station in the machine. Uncut bridge portions O provide the junction between two adjacent blanks.

In the same mechanism 101 but at a later stroke, the bridge portion O between blanks N is cut through to sever this closure element blank N from the web. Following this severing operation and as a final step the plug section B is drawn in the blank N and this completes the forming of a closure element A. After the opera-

tions have once been started, two completed elements A result at each operating stroke of the mechanism 101.

The cutting and drawing operations incidental to the complete forming of the closure elements A, is brought about by cooperating punch die members which preferably are included in the mechanism 101 and between which the web passes. These members include a stationary die block 104 (Figs. 2, 3, 6, 15 and 16) and vertically movable cooperating punches 105. The die block 104 is secured to a bolster plate 106 bolted to the frame bed 33.

The top of the die block is flush with the path of travel of the web so that the latter will readily advance across it. A stripper plate 107 is disposed above the block to hold the web against upward displacement. The die block is formed with openings 108 which correspond in shape to the areas K, L and M to be cut from the web while the stripper plate, the bolster plate and the frame bed are formed with slightly larger clearance openings 109 of the same general shape.

The punches 105 are disposed above the web C and cooperate with the die block openings 108 in cutting the areas K, L and M from the web. For this purpose the punches are mounted in a punch head 115 (Figs. 1, 3, 6, 7 and 16) which is bolted to a vertically movable cross-head 116. The cross-head extends transversely of the machine and each end is secured to the upper shouldered ends of a pair of spaced and parallel vertical actuating rods 117. The cross-head is held in place by locknuts 118.

The actuating rods 117 extend down through guide bearing brackets 121 which are bolted to the top of the frame bed 33, there being two brackets on each side of the machine as best shown in Fig. 2. The guide brackets are located in clearance openings 122 in the frame bed and provide long bearings for the rods. The lower ends of the rods 117 are shouldered and are secured by nuts 124 to an actuating member 125. This member holds all four of the actuating rods 117.

The actuating member 125 is held in vertical alignment by a pair of spaced and vertical pilot pins 128 (Figs. 6 and 7) which are secured in the frame bed 33 and which extend down through slide bearings 129 formed in the member. Collars 131 secured to the lower ends of the pilot pins limit the travel of the member.

Actuating member 125 is moved up and down by a shoulder stem 132 which is carried in a bearing 133 disposed in the middle of the actuating member. Member 125 rests on the shoulder of the stem while a compression spring 135 surrounds the upper end of the stem and is interposed between the bearing 133 and a collar 136 on the stem. This provides a flexible or yieldable connection between the member and the stem.

The lower end of the stem 132 carries a swivel head 141 (see Fig. 3) which is mounted on a pivot pin 142 in the stem. Opposite sides of the head are pivotally connected to a pair of angularly disposed eccentric arms 143 which operate on eccentrics 144 mounted on the main drive shaft 78. The eccentrics are arranged to vertically reciprocate the stem 132 while maintaining it in vertical alignment and thereby prevent any side shifting of the actuating member 125 so that binding on its pilot pins 128 will be eliminated.

Thus as the main drive shaft 78 rotates, it revolves the eccentrics 144 and hence through

the eccentric arm 143, raises and lowers the actuating member 125. This vertical movement of the actuating member shifts the actuating rods 117 and thus raises and lowers the cross-head 116 and the punches 105 carried therein. On the downward stroke of the crosshead, the punches cooperate with the die block 104 and cut away the scrap portions of the web C to shape the closure element blank N as hereinbefore explained.

Severing of a completely shaped closure element blank N from the web C is effected by a tubular cut-off knife 151 (Fig. 16) which is carried in the punch or crosshead 116. There are two of these cut-off knives, one for each longitudinal row of closure element blanks N in the web. Each knife is formed with a cutting or shearing edge 152 which cooperates with a similar edge 153 on the die block 104 in cutting across the bridge O (Fig. 17) which connects the closure element blank N to the web.

The severing operation is effected on the down stroke of the cross-head 116 and on this same stroke the cut-off knife pushes the severed blank 154 N down into place on a draw ring 156 for the drawing operation. The draw ring is seated in a stepped recess 157 located in the bolster plate 106. Within the ring there is an ejecting plunger 158. The plunger is normally held in a position flush with the top of the draw ring, by a compression spring 159 which is housed within the plunger and which exerts its pressure against the frame bed 33.

After moving the sheared off blank N down onto the draw ring 156, the tubular cut-off knife 151 momentarily remains stationary at the bottom of its stroke to hold the blank with a slip grip for and during the drawing operation. This drawing operation immediately follows the cutting off operation and produces the plug section B in the blank.

The drawing of the plug sections B in the blanks N is brought about by drawing punches 165 (Fig. 16) which are carried in the tubular cut-off knives 151. There is one of these punches for each knife and they extend up through clearance holes 166 in the punch head 115, and in the cross head 116 and are secured at their upper ends in an auxiliary cross head 171 (Fig. 6). The upper ends of the punches are threaded and are locked in the auxiliary cross head by locknuts 172 which permit of adjusting the punch vertically to obtain a desired depth of draw in the blanks N.

55 The auxiliary cross head 171 is mounted directly above the cross head 116 and is actuated independently of cross head 116. For this purpose the ends of the auxiliary cross head are secured to the upper shouldered ends of vertical actuating rods 175. There is one of these rods at each end of the auxiliary cross head and they are disposed between and in line with the two actuating rods 117 of the cross head 116 (see Fig. 2).

60 These rods 175 extend down through guide holes 176 (Fig. 6) in the cross head 116, holes 177 in the frame bed 33, and holes 178 in the actuating member 125. Below the actuating member 125 the lower end of each actuating rod 175 terminates in a clevis 181 which carries a pivot pin 182 for a crank arm 183 mounted on a crank 184 formed in the main drive shaft 78. There are two of these cranks 184, one for each actuating rod 175.

65 Hence rotation of the main drive shaft 78 also

operates the crank arms 183 and thus through the actuating rods 175, raise and lower the auxiliary cross head 171 and its drawing punches 165 in time with the movement of the cross head 116. It is this timing that performs the drawing of the plug section B in the cut-off blank N at the proper instant and thus converts the blank into a closure element A ready to be assembled with its end member D.

The end members D are retained in stacks in a pair of magazines 186 (Figs. 1, 2, 3, 9 and 10), which are located one on each side of the machine just outside of and adjacent the path of travel of the web C. These magazines include vertical guide bars 187 which are secured in magazine bases 188. The bases are secured to runway blocks 189 bolted to the frame bed 33. The guide bars are arranged around an opening 190 in each magazine base and the lower part of each stack of end members extends down into its associated opening and is supported on the runway 189.

The end members D are fed from the bottom of the magazine one at a time by a short stroke bar 191 (Figs. 9 and 10) which extends under the magazine. There is one of these stroke bars for each magazine 186 and they are disposed in side grooves 192 (see also Fig. 13) formed in the runways 189. Each stroke bar is reciprocated through a forward or feeding stroke and thence through a return stroke by a segment gear 193 which meshes with a rack 194 formed on the stroke bar.

The two segment gears 193 are formed on a pair of arms 195 both being mounted on a cross shaft 196 carried in bearings 197 which depend from the frame bed 33. The shaft extends outside of the frame bed on one side and carries a cam arm 198 (see also Figs. 2 and 3) having a cam roller 199 which operates in a cam groove 200 of a barrel cam 201 mounted on the cam shaft 65. It is this cam shaft therefore that reciprocates the stroke bars 191.

Each stroke bar 191 carries a feed finger 202 which is spring held and is depressible within its bar. The feed finger 202 is located on the forward end of its stroke bar and in one position of the bar is just behind the magazine 186. Hence when a stroke bar moves through a forward stroke the feed finger engages behind the lowermost end member D in the stack and pushes it out from under the others in the stack. The feed finger pushes the end member into the grip of a pair of rotating feed rollers 203, 204 (Figs. 9 and 10) which are located adjacent the inner end of each stroke bar.

Feed roller 203 is disposed above the roller 204 and is mounted on a short shaft 205 journaled in bearings 206 formed in the magazine base 188. Roller 204 is mounted on a shaft 207 journaled in a bearing in the runway 189 and in a bearing bracket 208 secured to the frame bed 33. The rollers are rotated in unison by gears 209, 210 mounted on the respective shafts 205, 207.

Shaft 207 is driven by an endless chain 211 which operates over a sprocket 212 on the shaft and over a driving sprocket 213 (Fig. 3) mounted on a cross shaft 214 (see also Fig. 6) journaled in bearings 215 in the leg section 34 of the main frame. The cross shaft 214 extends outside of the main frame and is driven by an endless chain 216 which operates over a sprocket 217 (see Figs. 1) on the shaft 214 and over a

driving sprocket 218 on the main driving shaft 78.

The feed rollers 203, 204 on each side of the machine feed the end members D into position in front of advancing fingers 221 of reciprocable feed bars 222 (Figs. 22 and 23) which are disposed adjacent the stroke bars 191. These feed bars extend for nearly the full length of the machine alongside of the path of travel of the web C and carry a plurality of the feed fingers 212 which are located in spaced order along the bars. This advances the end members D in a step-by-step movement in time with the web C, and along the top of the runways 189.

Pressure rails 223 (Fig. 10) disposed along the outer edges of the runways overlap the end members D passing therealong and thus frictionally hold them against return with the advancing fingers when the latter move back on a return stroke of the feed bars.

The feed bars 222 are disposed in slideways 224 (Figs. 22 and 23) formed in the runways 189. Adjacent one end, each bar is formed with a rack 225 which extends down through an opening 226 in the runway and which meshes with a segment gear 227. The segment gear is formed on an upright arm of a bell crank 228 mounted on and keyed to a rocker shaft 229. There are two of these bell cranks, one for each feed bar 222.

The rocker shaft 229 extends transversely of the machine and is carried in a pair of spaced bearings 230 which depend from the bottom of the frame bed 33. One of the bell cranks 228 is connected by a link 231 to an eccentric 232 (see also Figs. 3 and 4) which is mounted on an eccentric shaft 233 (see also Fig. 1) journaled in bearings 234 in the leg section 34 of the machine frame. The eccentric shaft is driven by an endless chain 235 which operates over a sprocket 236 on the shaft and over a driving sprocket 237 on the main drive shaft 78.

Hence the rotation of the main drive shaft 78 revolves the eccentric shaft 233 and this through the eccentric 232 rocks the rocker shaft 229. Rocking of this shaft rocks the bell cranks 228. It is this rocking of the bell cranks that reciprocates the two feed bars 222 through a forward or feeding stroke to advance the end members D along the runways 189 and thence through a return stroke.

Because of the staggered arrangement of the closure elements A in the web C, an end member D advancing along one runway 189 moves through one idle station before being introduced into an assembly station 247 (Fig. 2). On the opposite side of the machine, an end member moving along its runway moves through two idle stations before entering the assembly station. These assembly stations are located adjacent the place where the closure elements A are formed after being severed from the web C.

While an end member D is at this assembly station 247 a finished closure element A is swept sidewise from its position on the ejector plunger 158 (Fig. 16) of the draw ring 156 to a position directly over the dispensing opening E of the end member. This shifting of the closure element is effected by a transfer arm 251 (Figs. 2, 14 and 15) having a curved hook end 252 which is engageable around the drawn plug section B of a closure element.

There are two of these transfer arms 251, one for each row of closure elements in the web C and they are arranged as best shown in Fig. 15. These

arms are secured to the upper ends of a pair of rocker shafts 254 (Fig. 14) which are carried in bearings 255 in the frame bed 33. The lower ends of the shafts carry meshing segment gears 256 so that the shafts and the arms may be rocked in unison.

One of the shafts also carries a segment bevel gear 257 which meshes with a similar gear 258 mounted on a rocker shaft 259 carried in bearings 261 in the frame bed 33. This rocker shaft extends outside the bed and carries a cam lever 262 having a cam roller 263 which operates in a cam groove 264 (see also Fig. 2) of a barrel cam 265 mounted on the cam shaft 65.

Thus as the cam shaft 65 rotates the cam 265, the latter rocks the cam lever 262 and the rocker shaft 259 and through the gear connection explained above rocks the vertical shafts 254. This rocking of the shafts 254 swings the transfer arms 251 through a transfer stroke from the position shown in dotted lines to that shown in full lines in Fig. 15 and thence through a return stroke to the dotted line position again. It is on the transfer stroke that the closure element A is picked-up and carried into the assembly station 247 as explained above. This transfer of the closure element is effected in time with the movements of the web C and of the end members D.

At the assembly station 247, the positioned closure element A is pushed down onto the end member D by an assembling plunger 271 (Fig. 7). There is one of these plungers for each assembly station and they extend up through the cross head 116 and are secured by locknuts 272 in the auxiliary cross head 171.

On the down stroke of the auxiliary cross head the plungers move down against the closure element. It is this movement that inserts the plug section B of the closure element into the dispensing opening E of the end member and thus assembles the parts for further advancement. On the return up stroke of the plunger the assembled parts are prevented from rising with the plunger, by a stripper plate 274 having a clearance opening 275 for the plunger (Fig. 9).

During this assembling operation the end member D is backed-up from below by a movable anvil 271 (Figs. 9 and 11) which is recessed to clear the plug section B of the closure element. The anvil is secured to a slide block 278 which is located in a vertical slideway 279 in the runway 189. A spring barrel 281 in the slide block exerts its force against the runway and thus presses the block down against a bearing block 282 on a crank 283 of a longitudinal rocker shaft 284 carried in bearings 285 in the frame bed 33.

The rocker shaft 284 on each side of the machine extends beyond the end of the machine as best shown in Fig. 9 and carries a segment gear 291 (see also Figs. 2 and 4). The two segment gears mesh with racks 292 formed in a transverse slide bar 293 which slides in brackets 294 secured to the end of the machine. The slide bar is connected by a link 295 to a cam lever 296 mounted on a pivot stud 297 threaded into the end of the trough extension 67 of the frame bed 33. The lever carries a cam roller which operates in a cam groove 298 of a face cam 299 mounted on the end of the cam shaft 65.

Hence the rotation of the cam 299 with the cam shaft 65, reciprocates the slide bar 293 and thus rocks the segment gears 291 and their shafts 284 in time with the other moving parts of the machine. This rocking movement of the shafts 284 swings the cranks 283 and thus raises and lowers 75 tions for each runway.

the anvils 277 against the resistance of the spring barrels 281, to back up the end member D while the closure element is being assembled with it and to withdraw the anvil to clear the plug section B of the assembled closure element so that the assembled parts may be further advanced along the runway 189 as a unit.

After such an assembling operation the closure unit is advanced by the feed bars 222 through an idle station and thence into a stapling station 311 (Fig. 2) where the staple F is inserted into the assembled parts to secure them together. The staples are formed from strands 312 (Figs. 1, 3 and 4) of wire taken from a pair of spools 313 located one on each side of the machine. Each wire strand enters a stapling device 314 disposed over the path of travel of the end members D on each side of the machine.

These stapling devices preferably are of the character disclosed in United States Patent 1,983,384, issued December 4, 1934, to Harry T. McCluse on Wire stitching machine, and United States Patent 2,034,408, issued March 17, 1936, to the same inventor, on Machine for fastening covers to containers.

The stapling devices 314 are secured to brackets 316 which are bolted to the top of the frame bed 33. The devices are operated by vertical plungers 317 (Fig. 3), the lower ends of which are connected by links 318 to levers 319 mounted on pivot pins 321 carried in lugs 322 formed on the bottom of the frame bed. There are two of these plungers and levers, one set for each stapling device and each lever is pivotally connected to an eccentric arm 324 of an eccentric 325. The two eccentrics are mounted on and are rotated by the eccentric shaft 233.

In the stapling devices 314 the wire strands 312 are cut into short lengths and are bent into U-shape to provide the staples F. The legs of a staple thus formed are driven through the assembled closure element A and through the end member D while they are at the stapling station. The ends of the staple then are bent back on the under side of the member. It is this stapling action that secures the element and the member together to produce the end closure unit hereinbefore mentioned.

During the insertion of the staple, the end member D is supported on an anvil 331 (Fig. 9) which bends back the ends of the staple as hereinbefore mentioned. The anvil is recessed to clear the plug section B of the closure element and is vertically movable to engage the end member during the inserting operation and to withdraw from the end member to permit its further advancement.

The anvil 331 is mounted on a slide block 332 which is located in a vertical slideway 333 in the runway 189 and is maintained under spring pressure of a spring barrel 334 in the same manner as the assembling anvil 271. The anvil and the slide block are raised and lowered in time with the other moving parts of the machine by a bearing block 335 mounted on a crank 336 of the crank shaft 284.

This stapling together of a closure element A and an end member D completes the operations on the end closure units and thereafter they are ready for discharge from the machine. In the instant machine the feed bars 222 propel the completed units through two idle stations along the runways 189 and then feed them into a re-stacking station. There is one of these stations for each runway.

At the re-stacking station a closure unit is received on a lifter pad 341 (Figs. 5 and 9) located under a vertical magazine 342. The pad is disposed within a slideway 343 formed in the frame bed 33 and in a magazine base 344 which is secured to the top of the frame bed. The top of the lifter pad is normally held flush with the runway 189 by a cylinder 345 formed on the rock shaft 284 and having a normally vertical flat cam side 340.

This cylinder is located within a recess 346 in the pad and operates against a shoe 347 in the pad. Slots 348 in the pad adjacent the recess permit the rock shaft to extend through the pad. The cylinder retains the lifter pad in a depressed position in its recess, under pressure of a plurality of compression springs 349 which press upwardly against the bottom of the pad. These springs are disposed in vertical bores 351 formed in a plate 352 secured to the bottom of the frame bed 33.

Hence when the rocker shaft 284 moves through a partial rotation to bring the assembling anvil 277 and the stapling anvil 331 into operating position, it also rotates the cylinder 345 and thus shifts its flat cam side 340 from its normally vertical position into a horizontal position. This shifting of the cylinder cam permits the springs 349 to lift the pad 341 and the closure unit carried thereon.

The closure unit is thus raised up through an entrance opening 355 in the magazine base 344 and is deposited at the bottom of a stack of such units retained in the magazine. The units are maintained in stacked order by a plurality of guide bars 356 which are secured in the base around the opening 355. Spring held catches 358 pivotally retained in recesses in the magazine base adjacent the entrance opening, support the units in the stack and readily permit the addition of new units to the bottom of the stack as these latter units are raised into position.

In this manner vertical stacks of the completed units are built up at the ends of the runways 189. These stacks may be removed manually from the magazines as desired.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a machine for making fibre container parts, the combination of means for severing a flat blank from a strip of fibre stock, means for drawing the severed blank into a closure element having a depressed drawn plug section, and devices for assembling and securing the closure element with an apertured container end member by inserting said plug section of the closure element into the aperture of said end member to produce a composite end closure unit.

2. In a machine for making fibre container parts, the combination of means for simultaneously severing a plurality of flat blanks from a strip of fibre stock, means for drawing the severed blanks into closure elements each having a depressed drawn plug section, and devices for assembling and securing the closure elements with apertured container end members by inserting said plug section of the closure element into

the aperture of said end member to produce a plurality of composite end closure units.

3. In a machine for making fibre container parts, the combination of means for feeding a flat strip of fibre stock along a predetermined path of travel, mechanism adjacent said path of travel for simultaneously forming and drawing a plurality of closure elements from said strip, each of said closure elements having a depressed drawn plug section, devices for shifting the newly formed closure elements into assembled position with co-operating flat end members each having an aperture therein, and instrumentalities for securing the assembled parts together by inserting said plug section of a closure element into the aperture of a said flat end member to produce composite end closure units.

4. In a machine for making fibre container parts, the combination of means for feeding a strip of fibre stock along a predetermined path of travel, mechanism adjacent said path of travel for forming and drawing from said strip a double row of closure elements each including a depressed drawn plug section, and devices for shifting the closure elements so formed in opposite directions into respective registry with a plurality of separately fed apertured container end members, and means for inserting the drawn plug sections of said closure elements into the registered and aligned apertures of said container end members to produce composite end closure units.

5. In a machine for making fibre container parts, the combination of means for feeding a strip of fibre stock along a predetermined path of travel, mechanism adjacent said path of travel for forming and drawing a double row of closure elements from said strip, each of said closure elements including a depressed drawn plug section auxiliary feeding means for advancing container end members along a predetermined path parallel with the strip and closely adjacent its outer edges, each of said end members having an aperture therein, devices for shifting the newly formed closure elements outwardly across the outer edges of the strip and into registering position above the advancing end members, means for pushing the positioned closure elements down on and into the apertures of the respective registered end members, and instrumentalities for securing the parts thus assembled together to produce composite end closure units.

6. In a machine for making fibre container parts, the combination of a die mechanism for forming a double longitudinal row of closure elements from a strip of fibre stock, a pair of magazines located one on each side of the strip of stock for retaining a supply of container end members, feeding devices adjacent said magazines for feeding the end members therefrom individually and in time with the forming of said closure elements and along paths of travel adjacent the strip, a pair of pivotally mounted transfer arms for engaging behind a pair of newly formed closure elements and for transferring them into positions onto a pair of the advancing end members, means for assembling the positioned closure elements with the end members, and instrumentalities for securing the assembled parts together to produce end closure units.

7. In a machine for making fibre container parts, the combination of means for intermittently feeding a strip of fibre stock along a straight line path of travel, auxiliary means for feeding two lines of end members having dispensing openings therein, along straight line

paths of travel in time with said strip, one line being on each side of and closely adjacent said strip, die mechanism adjacent the path of travel of the strip for forming pairs of closure elements from two longitudinal rows in the strip, each closure element having a drawn plug section, devices adjacent said die mechanism for sweeping the individual closure elements of each pair in opposite directions and into position adjacent said end members, vertically movable plungers located above the path of travel of the end members for assembling the closure elements with the end members by inserting the drawn plug sections of the elements into the dispensing openings of the end members, and instrumentalities for stapling the assembled parts together to produce end closure units.

8. In a machine for making fibre container parts, the combination of means for intermittently feeding a strip of fibre stock along a straight line path of travel, auxiliary means for feeding two lines of end members having dispensing openings therein along straight line paths of travel in time with said strip and one line on each side of and closely adjacent said strip, die mechanism adjacent the path of travel of the strip for forming pairs of closure elements from two longitudinal rows in the strip, each closure element having a drawn plug section, devices adjacent said die mechanism for sweeping the individual closure elements of each pair in opposite directions and into position adjacent said end members, vertically movable plungers positioned above the path of travel of the end members for assembling the closure elements with the end members by inserting the drawn plug sections of the elements into the dispensing openings of the end members, instrumentalities for stapling the assembled parts together to produce end closure units, an anvil for each of said plungers and for each of said stapling instrumentalities for supporting the end members during the assembling and the securing of the parts, and means for simultaneously shifting said anvils into and out of operative position in time with the travel of said strip.

9. In a machine for making fibre container

parts, the combination of a die mechanism for forming double longitudinal rows of closure elements from a strip of fibre stock, a pair of magazines located one on each side of said strip for retaining a supply of container end members, feeding devices adjacent said magazines for feeding the end members therefrom individually and in time with the forming of said closure elements and along paths of travel adjacent the strip, a pair of pivotally mounted transfer arms for engaging behind a pair of newly formed closure elements and for transferring them into positions onto a pair of the advancing end members, means for assembling the positioned closure elements with the end members, instrumentalities for securing the assembled parts together to produce end closure units, and a discharge magazine at the end of each of the paths of travel of the end members for receiving completed end closure units and for retaining them in stacks.

10. In a machine for making fibre container parts, the combination of a die mechanism for forming double longitudinal rows of closure elements from a strip of fibre stock, a pair of magazines located one on each side of said strip for retaining a supply of container end members, feeding devices adjacent said magazines for feeding the end members therefrom individually and in time with the forming of said closure elements and along paths of travel adjacent the strip, a pair of pivotally mounted transfer arms for engaging behind a pair of newly formed closure elements and for transferring them into positions onto a pair of the advancing end members, means for assembling the positioned closure elements with the end members, instrumentalities for securing the assembled parts together to produce end closure units, a discharge magazine at the end of each of the paths of travel of the end members for receiving completed end closure units and for retaining them in stacks, a magazine for receiving the said closure units, and stacking devices for inserting individual units into said magazine at the bottom of the stack within the magazine.

JOHN H. MURCH.
